UNITED STATES PATENT OFFICE.

JEAN F. WEBB, SR., OF NEW YORK, N. Y.

SUBMARINE SAFETY APPARATUS.

Application filed February 18, 1925, Serial No. 10,110. Renewed May 24, 1926.

The invention generally relates to safety apparatus for submarines and has for its object to provide means for facilitating quick relief and rescue of imprisoned crews of submarine vessels that have been accidentally sunk, by injury due to collision, or mechanical failure, and which are unable to rise again to the surface of their own power, or which are in none the less dangerous position by having been cast upon a wave dashed reef or bar because of mechanical failure or faulty navigation.

More specifically, the invention resides in the provision of certain new and useful improvements over the disclosure of my invention made in application for patent Serial Number 710,748, filed by me on May 3, 1924. These improvements have for their object to provide means for more practically mounting the air induction cable storing reel in a manner providing for a more convenient ejection of the torpedo float without interference with the normal functions of the torpedo tubes and without unduly encroaching on the much needed compartment capacity of the vessel, and also the provision of means for so applying the broad crew-sustaining air induction features as to adapt them for use in emergencies where the vessel is stranded upon a reef or bar where torpedo float ejection would be either impractical, unnecessary or undesirable.

With the above and other objects in view the invention further resides in the novel details of construction, combination and arrangement of parts, first fully described in the following detailed specifications, then particularly pointed out in the appended claims, and illustrated in the accompanying drawings, in which:—

Figure 1 is a diagrammatic side elevation illustrating both phases of use of the invention, the air induction through the torpedo float sustained cable or deep water use, and air induction through the rigid stand-pipe or shallow water use.

Figure 2 is a side elevation of the torpedo float.

Figure 3 is an enlarged detail longitudinal section of the nose end of the torpedo float.

Figure 4 is an enlarged detail longitudi-

dinal section of the lower end of the torpedo float.

Figure 5 is a side elevation and part section illustrating the stand-pipe air induction connections.

Figure 6 is a horizontal section illustrating the cable winding reel mounted on the breech-block of a torpedo tube.

Figure 7 is a vertical cross section of the reel and its mountings.

Figure 8 is a somewhat diagrammatic section indicating several compartments of a vessel and a means for ventilating them singly or collectively.

In the drawings 1 indicates a submarine vessel of any of the types now used, 2 the torpedo tube, and 3 the operating compartment thereof.

A torpedo shaped float 4 is provided and is shaped to be adapted for ejection through a torpedo tube, and, when its use is unnecessary, for being stored with the usual torpedo equipment.

The float 4 comprises a copper shell 6 encased by staves 7 of balsa or other wood which will aid its buoyancy and protect it against wave dashed flotsam. A conical protective and weed penetrating nose 8 is fitted over one end of the float.

A rigid air supply conductor pipe 9 extends through the float 4 and has secured thereto, as at 10, the upper end of a wire covered air supply hose or hollow armored cable 11, adapted to be carried to the surface of the sea by the float when ejected or released, and having its lower end in communication with the interior of the sunken vessel to supply air thereto.

The upper end of the pipe 9 extends into the protective nose 8 and has secured thereto inwardly and outwardly opening check valves indicated 12 and 13 respectively.

In addition to its air conducting function the pipe 9 and hose connection 11 serve to encase the electricity conducting connection 14 which is connected with a source of electrical energy supply inside the vessel and, through insulated bushings and sockets, with the signal lights within the nose 8, see Figure 3.

To render visible the signal lights and

for protecting the valves against clogging, the nose 8 is screened-windowed at 15.

The hose 11 is wound around and secured to a hollow reel 16 in a manner whereby it will communicate with the interior of the same as shown in Figures 6 and 7.

The reel includes hollow trunnions 17 for which air and water-tight bearings are provided at 18 in the opposite ends of the reel 10 housing 19 and through one of which swivel connection is made with the breather pump 20, as at 21, while the other is equipped at 22 to facilitate the electrical energy connection referred to.

15 While the reel housing 19 may be mounted in the submarine compartment in any desired manner, I here disclose a particularly simple, practical and convenient manner of mounting the same.

20 The housing may be constructed of boiler iron and of hollow cylindrical shape and, in the wall thereof, is formed a well curved discharge throat 23 serving as a passage for the hose 11 and which is surrounded by a se- 25 curing flange 24.

The flange 24 is air and water-tight secured, as at 25, to the flange 26 of any well known type of breech-block 27. I desire to mount the housing on the breech-block be- 30 cause of the great possibilities of compactness and for the reason that such mounting is practical without interference with ordinary torpedo tube usage.

35 The usual interrupted thread equipment of the breech-block is indicated at 28 while 29 serves to indicate the carrying frame therefor which is hinged, as at 30, to suitable hinge ears carried either by the submarine compartment wall or the loading end of the 40 torpedo tube.

A lever for suitably turning the breech-block is generally indicated at 31 and the said breech-block has a well curved central aperture 32 for permitting free passage of 45 the cable 11 therethrough when the float 4 is ejected.

A hand brake 33 may be provided to control paying out of the air hose 11, also a revolution counter 34 if desired, for counting revolutions of the reel to ascertain the depth of the vessel when the float 4 is released and reaches the water's surface.

45 A crank 35 may be provided to facilitate reeling in of the hose 11 when desired.

55 The staves of the float 4 may be secured by bands 36 and caps 37 provided to strengthen the ends thereof. It may also be provided with a rubber gasket 38 at its lower or rear end to effectively seal the tor- 60 pedo tube and facilitate its compressed air ejection when that method is used, and a bearing member 39, chain connected thereto at 40, and serving to prevent injurious flex- ing of the hose 11 at its point of connection.

The foregoing serves to describe the tor- 65 pedo float and its connections whereby it may be ejected or released to serve as a means for supplying fresh air to the interior of the sunken vessel, for signalling its position to rescuers, and for indicating to 70 the imprisoned crew the depth at which their vessel lies, in the manner following.

Assuming an emergency where the submarine crew is trapped and resting on the ocean floor. The men first close the outer 75 sea door of the vessel (not shown) then drain the water out of the torpedo tube 2 and also out of the housing 19 through the drain cock 41 with which the housing is provided. The breech-block 27 is then operated 80 and swung open in the usual manner, the float 4 secured at 10 to the reeled hose 11 and inserted into the torpedo tube 2, the breech-block again secured, the outer sea door opened and the float 4 ejected by air 85 pressure which may be applied at 42 into the housing and torpedo tube if desired.

The float 4 may, of course, be ejected by explosives or by hand if desired.

Just before ejecting the float 4 the pump 90 is operated to force air into the reel and the coils of the hose 11 so that when the float is ejected the hose will be more buoyant and not subject to collapse by water pressure; also, to balance the inside and outside pressure on the valves 12 and 13 to prevent inflow of water, it being understood that water pressure is tending to open 12 and close 13 while air pressure is tending to close 12 and open 13 while the float is rising to the surface. Should any slight amount of water gain entrance it will be expelled by air pressure as the float reaches the surface.

When the float 4 reaches the surface the pump action is reversed to its suction function and a fresh supply of air furnished the imprisoned crew. Thereafter by alternating the pump action fresh and foul air may be inhaled into and exhaled out of the interior of the sunken vessel to sustain the crew, and this constant current of air will aid in keeping the hose expanded from float to vessel.

Obviously, any type of double acting pump 20 may be employed.

By noting the revolutions recorded on the counter 34 the depth from surface to vessel may be computed.

The electrical connection 22 need now but be applied and secured tightly to light the lights within the protective nose 8 (or sound an audible signal if it be desired to provide such) and the crew will be safely sustained and their rescuers signalled to. The electric connections may also be used for telephoning by use of proper connections above and below.

As hereinbefore stated, the improved

means for mounting the winding reel, and the provision of means for providing for crew sustaining air induction or ventilation of a vessel stranded in shallow water where 5 torpedo float ejection is impossible, impractical, or undesirable, form the subject matter of my present invention.

I have already clearly described the first 10 of the above features, i. e., the reel mounting, and the description of the latter feature will now follow.

At a point closely adjacent the conning tower 43 of the vessel, preferably behind the same so as to provide a protection against 15 sea wash, I provide a hollow stand-pipe 44 secured to and passing downwardly through the deck of the vessel into the compartment 3 thereof and having its lower projected end provided with a globe valve 45, for closing 20 off communication with the interior of the vessel when desired, and a union connection 46, whereby ready connection with the double acting pump 20 may be effected.

The pipe 44 may also be provided with 25 an upper globe valve 47 which may be operated from without to close off communication through the said pipe if desired.

This stand-pipe 44 is designed to effect the same function as that of the pipe 9 and 30 cable 11 and for that purpose has the upper end thereof equipped with inwardly and outwardly opening check valves 48 and 49 which serve the same function as the valves 12 and 13 with which that pipe 9 is equipped 35 and which has been hereinbefore described in detail, and a downturned pipe section 50 effectively serving to prevent ready splashing of waves into the upper end of the pipe 44.

40 It will be readily understood that should the submarine become stranded on a reef or bar in relatively shallow water, the upper end of the pipe 44 would project above the level of the water and, by attaching and operating 45 the pump 20 as hereinbefore described the interior of the vessel could be conveniently ventilated. It will also be obvious that this simple means may be utilized as a ventilating device under normal conditions 50 when the vessel is functioning perfectly and running on the surface or awash. In this case, when driving is contemplated, communication with the interior of the vessel would be cut off by use of either or both 55 of the valves 45 and 47.

The stand pipe 44 may, of course, be constructed in a single tubular section as indicated in Figure 1, but it may be found desirable to construct the same of two or more 60 telescopic sections as illustrated in Figure 5, water-tight gland connections 51 being provided to prevent water leakage into the said piping. Also, as conning tower structures 65 are now becoming quite massive, sufficiently so as to facilitate mounting of heavy guns

thereon, it may be found desirable to project the piping 44 up through that tower structure as indicated in Figure 5. With such an arrangement the upper section of the telescopic piping 44 could be connected at 52 to move vertically with the periscope 53. This would be very practical as the apparatus could be utilized to ventilate the vessel at any time that vessel was in a position for projecting its periscope into position for use. 70 In this arrangement the upper end of the piping 44 could be positioned just below the eye of the periscope to prevent obstruction of vision therethrough and the valve 47 positioned in the uppermost one of the telescopic sections. 80

In Figure 8 I have illustrated an additional modified feature of the invention in which means is provided for ventilating all 85 or a selected one or ones of the individual compartments into which the submarine vessel may be divided.

In the disclosure last referred to one passage (inlet or outlet) of the double acting pump 20 is connected, through the union 54 and flexible hose coupling 55, with the union 46 with which the internally extending end of the stand-pipe 44 is equipped, and the other passage (inlet or outlet) of said pump is connected with the ventilating pipe line 90 95 56 which passes through all or desired ones of the compartments of the vessel and through which proper ventilation of such compartments is effected. The partitions which divide the main compartment or interior of the vessel into the individual compartments mentioned are diagrammatically indicated at 57. 100

In each individual compartment formed between the partitions 57 an intake or outlet 105 funnel 58 is connected with the pipe line 56 and in controllable communication therewith through the valve connection 59.

As foul gases such as it is desirous to expel from the compartments of the vessel sink 110 to the level of the floor of those compartments each funnel 58 is located closely adjacent the floor of the compartment it serves so as to most effectively function to draw the poisonous gases off therefrom through the pump, then acting in its exhaling capacity, and to atmosphere through cable 11, pipe 9 and valve 13, or through stand-pipe 44 and valve 49 according to the connection of the flexible hose section 55, to the hollow reel at 21 in the first instance, or to the union 46 as illustrated in Figure 8 and as last described. When the action of the pump is reversed the fresh air will be discharged 115 into the compartments through the funnels and rise to fill those compartments. 120

It will be obvious that the whole of the system of funnels 58 throughout the line 56 may be utilized at once or, by manipulating 125 the valves 59 the whole ventilating function 130

may be confined to the relief and service of a single compartment or selected sets thereof as the need may demand.

- This feature of submarine vessel ventilation 5 will be found very convenient for ventilation of the interior of such vessels under normal running conditions as above related and occasional use of the system will insure a pure atmosphere in the entire vessel, and such 10 use of the apparatus is especially desirable at night when the carbon dioxide created by the sleeping occupants will settle to the floor and be properly drawn off and replaced by fresh air from above the water's surface.
- 15 The provision of the flexible hose length 55 serves to facilitate quick and convenient connection of the pump 20 with either the stand-pipe 44 or the reel 19.

From the foregoing description, taken in 20 connection with the accompanying drawings, it is thought that the novel details of construction of my improved submarine safety apparatus features, the manner of operation and advantages thereof, will be readily apparent to those skilled in the art to which 25 they relate.

What I claim is:

1. In submarine ventilating apparatus of the kind wherein a float is adapted to be 30 ejected through the torpedo tube of the vessel and carry a hollow cable to the surface; a reel on which said cable is wound, a casing in which said reel is mounted, a breech-block for cooperation with the entrance of 35 the torpedo tube of the vessel, and means mounting said casing on said breech-block, said breech block having a passage through the same for the cable.

2. In submarine ventilating apparatus of 40 the kind wherein a float is adapted to be ejected through the torpedo tube of the vessel and carry a hollow cable to the surface; a reel on which said cable is wound, a casing in which said reel is mounted, a breech-block for cooperation with the entrance of 45 the torpedo tube of the vessel, and means mounting said casing on said breech-block, said breech block having a passage through the same for the cable, said casing being in 50 water-tight connection with said breech-block whereby water entering same through the breech-block passage when the torpedo tube is open to eject the float will be trapped against entering the interior of the vessel.

3. In submarine ventilating apparatus of 55 the character described, the combination with the breech-block of the torpedo tube thereof, said breech-block having a passage through itself; a hollow cable-carrying reel 60 and a casing therefor mounted on said block, said cable being adapted to pass through said breech-block passage, means for passing air through said cable, means for draining water from said casing, and means adapted 65 to pass through the torpedo tube of the ves-

sel for carrying an end of said cable to the surface of the water.

4. In submarine ventilating apparatus of the character described, the combination with the breech-block of the torpedo tube 70 thereof, said breech-block having a passage through itself; a hollow cable-carrying reel and a casing therefor mounted on said block, said cable being adapted to pass through said breech-block passage, means for passing 75 air through said cable, means for draining water from said casing, and torpedo shaped float adapted to pass through the torpedo tube of the vessel for carrying an end of said cable to the surface of the water, and 80 means for connecting a compressed air blast into the casing for ejecting the torpedo shaped float.

5. In submarine ventilating apparatus of the kind wherein a float is adapted to be 85 ejected through the torpedo tube of the vessel and carry a hollow cable to the surface; a reel on which said cable is wound, a casing in which said reel is mounted, a breech-block 90 for cooperation with the entrance of the torpedo tube of the vessel, and means mounting said casing on said breech-block, said breech-block having a passage through the same for the cable, said casing being in air and water-tight connection with said breech-block whereby water entering same through the breech-block passage when the torpedo tube is open to eject the float will be trapped against entering the interior of the vessel, means for draining water from the 100 casing, and means for connecting a compressed air blast into the casing for ejecting the float.

6. In submarine ventilating apparatus of the kind wherein a float is adapted to be 105 ejected through the torpedo tube of the vessel and carry a hollow cable to the surface; a reel on which said cable is wound, a casing in which said reel is mounted, a breech-block for cooperation with the entrance of 110 the torpedo tube of the vessel, and means mounting said casing on said breech-block, said breech-block having a passage through the same for the cable, the said reel being so proportioned and mounted upon the 115 breech-block in cooperation with the usual mounting of that breech-block as not to interfere with free normal use of the torpedo tube it cooperates with.

7. In means for ventilating submarine, a 120 stand-pipe projected from the deck of the vessel and at its lower end communicating with the interior thereof, oppositely operative check valves for said pipe, and means inside the vessel for drawing in and expelling air through said stand-pipe.

8. In means for ventilating submarines, a stand-pipe projected from the deck of the vessel and at its lower end communicating 125 with the interior thereof, oppositely opera-

- tive check valves for said pipe, and means inside the vessel for drawing in and expelling air through said stand-pipe, said stand-pipe comprising telescopic sections.
5. 9. In means for ventilating submarines, a stand-pipe projected from the deck of the vessel and at its lower end communicating with the interior thereof, oppositely operative check valves for said pipe, means inside the vessel for drawing in and expelling air through said stand-pipe, and shut-off valves for closing the passage through the stand-pipe when desired.
10. In means for ventilating submarines, a stand-pipe projected from the deck of the vessel and at its lower end communicating with the interior thereof, oppositely operative check valves for said pipe, means inside the vessel for drawing in and expelling air through said stand-pipe, said stand-pipe comprising telescopic sections, and a shut-off valve in each of the sections for closing the passage through the said sections when desired.
15. 11. In means for ventilating submarines, a stand-pipe projected from the deck of the vessel and at its lower end communicating with the interior thereof, oppositely operative check valves for said pipe, means inside the vessel for drawing in and expelling air through said stand-pipe, said stand-pipe comprising telescopic sections, and a shut-off valve in each of the sections for closing the passage through the said sections when desired; the valve in the lower section being positioned within the interior of the submarine.
20. 12. In means for ventilating submarines, having vertically adjustable periscope equipment, a stand-pipe projected from the deck of the vessel and at its lower end communicating with the interior thereof, oppositely operative check valves for said pipe, and means inside the vessel for drawing in and expelling air through said stand-pipe, said stand-pipe comprising telescopic sections, the upper one of the telescopic sections being connected to the periscope to be moved vertically therewith.
25. 13. In means for ventilating submarines, having vertically adjustable periscope equipment, a stand-pipe projected from the deck of the vessel and at its lower end communicating with the interior thereof, oppositely operative check valves for said pipe, and means inside the vessel for drawing in and expelling air through said stand-pipe, said stand-pipe comprising telescopic sections, the upper one of the telescopic sections being connected to the periscope to be moved vertically therewith, the upper end of the stand-pipe terminating short of the upper end of said periscope.
30. 14. In means for ventilating submarines, a stand-pipe projected from the deck of the vessel and at its lower end communicating with the interior thereof, oppositely operative check valves for said pipe, and means inside the vessel for drawing in and expelling air through said stand-pipe, the said stand-pipe having a down-turned pipe section at its upper end above the check valves.
35. 15. In means for ventilating submarines, a stand-pipe projected from the deck of the vessel and at its lower end communicating with the interior thereof, oppositely operative check valves for said pipe, and means inside the vessel for drawing in and expelling air through said stand-pipe, the entrance of each said check valve being down-turned for the purposes specified.
40. 16. In submarine ventilating apparatus of the character described, the combination with the breech-block of the torpedo tube thereof, said breech-block having a passage through itself; a hollow cable-carrying reel and a casing therefor mounted on said block, said cable being adapted to pass through said breech-block passage, means for passing air through said cable, means for draining water from said casing, and means adapted to pass through the torpedo tube of the vessel for carrying an end of said cable to the surface of the water, and air conducting means connectible in communication with the hollow cable and passing through the various compartments of the vessel, the communication thereof with each such compartment being valve controlled.
45. 17. In submarine ventilating apparatus of the character described, the combination with the breech-block of the torpedo tube thereof, said breech-block having a passage through itself; a hollow cable-carrying reel and a casing therefor mounted on said block, said cable being adapted to pass through said breech-block passage, means for passing air through said cable, means for draining water from said casing, and means adapted to pass through the torpedo tube of the vessel for carrying an end of said cable to the surface of the water, and air conducting means connectible in communication with the hollow cable and passing through the various compartments of the vessel which said means includes an intake or exhaust connection for each compartment having a funnel positioned close to the floor of each such compartment and in valve controlled communication with said air conducting means.
50. 18. In means for ventilating vessels, a stand-pipe projected from the deck of the vessel and at its lower end communicating with the interior thereof, oppositely operative check valves for said pipe, a double acting pump inside the vessel for drawing in and expelling air through the stand-pipe, and air conducting means connectible in

8
communication with the pump and passing through the various compartments of the vessel the communication thereof with each such compartment being valve controlled.

5 19. In means for ventilating submarines, a stand-pipe projected from the deck of the vessel and at its lower end communicating with the interior thereof, oppositely operative check valves for said pipe, means inside 10 the vessel for drawing in and expelling air through said stand-pipe, and air conducting

means connectible in communication with the hollow cable and passing through the various compartments of the vessel which said means includes an intake or exhaust connection for each compartment having a funnel positioned close to the floor of each such compartment and in valve controlled communication with said air conducting means. 15

JEAN F. WEBB, Sr.
